THERMOSTATICALLY-CONTROLLED FLUID
MIXING UNIT

George E. Ames, Oakland, Calif., assignor of one-fourth to William E. Joost, one-fourth to Leon A. Rice, and one-fourth to William J. Vaughan, all of Oakland, Calif.

Application July 3, 1933, Serial No. 678,894

2 Claims. (Cl. 236—12)

The invention relates to a means by which liquids or gases supplied from independent sources and at different temperatures may be mixed for dispensing from a common orifice and at a selective temperature.

An object of the invention is to provide a means of the character described in which fluid in any amount desired, and at any desired temperature within the range of the device, will be available at the common discharge orifice regardless of variations in the pressure of the fluids supplied the device from the independent sources.

Another object of the invention is to provide a means of the character described, in which the discharge of fluid from the device at a temperature exceeding that selected by the user cannot take place to any appreciable extent should the temperature as well as the pressure of the fluid at either of the supply sources become materially greater than normal.

A further object of the invention is to provide a unit of the character described which will be extremely sensitive to variations in temperature and pressure of the fluid therein and correspondingly active in the necessary compensation for maintaining the selected conditions.

A still further object of the invention is to provide a unit of the character described which will insure proper mixing of the different incoming fluids and at the same time allow communication of the latter with the thermostatic element only after complete mixture thereof has taken place.

The invention possesses other objects and features of advantage, some of which, with the foregoing, will be set forth in the following description of the preferred form of the invention which is illustrated in the drawing accompanying and forming a part of the specification. It is to be understood, however, that variations in the showing made by the said drawing and description may be adopted within the scope of the invention as set forth in the claims.

Referring to said drawing:

Figure 1 is a side view of the unit of my invention with parts broken away.

Figure 2 is a vertical sectional view of the unit.

Figure 3 is a fragmentary front view of the unit.

Figures 4 and 5 are transverse sectional views of the unit taken on the lines 4—4 and 5—5 of Figure 2.

In the embodiment of the invention illustrated, the unit 2 is used in connection with a hot water supply pipe 3 and a cold water feed pipe 4, and designed to afford a supply of water of selected

temperature from a common outlet 5 with any number of branches 6—valve controlled or otherwise. Preferably the unit comprises a casing 7 having inlet connections 8 and 9 for the hot and cold water pipes 3 and 4 respectively. 60

Fixed within the casing is a cylindrical sleeve or liner 12 having one or more ports 13 in direct communication with the hot water inlet, and one or more ports 14 in corresponding association with the cold water inlet. Mounted for reciprocation in the cylinder 12 is a sleeve 16 having ports 17 and 18 approximately of the same size as and arranged for registration with the ports 13 and 14 respectively. As will be clear from Figure 2, the ports 17 and 18 are so located with respect to each other and with the ports 13 and 14 that when the sliding sleeve is in a position causing full registration of ports 13 and 17, the ports 14 and 18 will be completely out of registration, and conversely when the ports 14 and 18 are in full registration, the ports 13 and 17 will be entirely out of registration. Likewise, the relationship of the ports is such that when the sleeve is moved to cause a greater or lesser aberration of one set of ports, the other set of ports 70 will move correspondingly to greater or lesser registration. The space within the sliding sleeve and the casing 7 into which the water from the ports 14 and 18 discharges is comparatively large and provides a chamber 19 wherein the streams 80 of water from the different inlets may be thoroughly mixed. Exit of the water from the chamber 19 is through one or more openings 21 here shown formed in a wall 22 of the casing, which serves to separate the chamber from a passage 23 85 for the mixed water. 90

By means of a spring 24 the sliding sleeve is urged to assume the position indicated in Figure 2, that is with the hot water ports 13 and 17 in full registration and the cold water ports completely closed. Preferably the movement of the sliding sleeve is limited so that in one extreme position the ports will be as just specified, and in the other extreme position the cold water ports will have moved to full open position while the hot water ports are completely closed. A convenient means of limiting the movement of the sleeve as aforesaid is by use of a pin 26 fixed to the sliding sleeve and engaging in a slot 27 in the fixed member 12. 100

The positioning of the slidable sleeve in the cylinder is arranged to be dependent on the temperature of the water contained in the passage 23, it being understood that it is from this passage that the water is ordinarily drawn off for con- 110

sumption. Disposed within the passage 23 and anchored at one end to the partition wall 22 is a 5 thermostatic element 28 which is here shown in the form of a tube and extends through the passage for a considerable length thereof. The element 28 has a relatively high coefficient of 10 expansion and is preferably formed of a material such as aluminum or the like. The movement of the tube 28 occasioned by the expansion or contraction thereof in accordance with the temperature of the water in the passage is communicated 15 to the sliding sleeve by means of a rod 29 secured to the free end of the tube and formed of a material having a relatively low coefficient 20 of expansion. The rod extends upward through the tube and through a hollow supporting post 31 solidly held in the chamber 19. At the upper extremity of the rod and adjustable longitudinally thereon is a member 32 which is designed 25 to engage a lever 33 fulcrumed for convenience on the post 31. The lever is engaged by the member intermediate the fulcrum point 34 and the end 35 engageable with the sleeve, and in order that a slight movement of the rod will effect 30 a more appreciable movement of the sleeve the member is designed to engage the lever much closer to the point 34 than to the end 35. For a more effective distribution of the force from the rod to the sleeve, a duplicate of the lever 33 is provided for engagement with the sleeve at a point diametrically opposed to the point engaged by the other.

The member 32 is here shown with a screw-threaded engagement with the rod so that rotation of the member on the rod will effect the 35 longitudinal adjustment of the member thereon. By means of a lock-nut 36 or the like the rod is secured to the tube in a manner preventing 40 rotative displacement of the rod, and on the other hand means manually operable and readily accessible to the user, are provided for effecting rotation of the member 32. The latter means, as here shown, includes a crank or handle 37 fixed 45 to a bevel gear 38 meshing with a bevel gear 39 formed as a part of member 32.

It will now be clear that since the element 28 is free to become extended or retracted at the 50 end connected to the rod, expansion or contraction of the element will produce a corresponding descent or ascent of the rod and accordingly the member 32. In this way as the latter is drawn 55 downwardly on expansion of the element, the lever will be proportionally depressed by the member and the slideable sleeve will be appropriately lowered to reduce the flow of water through the hot water ports and in like ratio increase the flow through the cold water ports. Likewise on 60 temperature conditions in the passage becoming colder and thereby effecting a contraction of the element the rod will rise and thus cause a corresponding release on the levers with the consequent elevation of the sleeve and a reduction and increase of the flow through the cold water and hot water ports respectively. It may be here 65 noted that since the axial displacement of the rod is at most relatively small, the desired engagement between the bevel gears will not be interfered with on said displacement.

In order that the operator may readily select 70 the temperature at which the water will be dispensed from the unit an indicator 41 is fixed to the control handle 37 and is arranged for co-operation with a dial 42 on which is delineated appropriate matter such as "hot", "medium", 75 "cold". When the pointer is positioned opposite

"hot" the member 32 will have been adjusted to assume its most elevated position on the rod so that regardless of the temperature of the water in passage 23 the sleeve will be positioned to cause full registration of the hot water ports and complete closure of the cold water ports. The device may be designed to render the sleeve at all times subject to the influence of the thermostatic element, or it may be so constructed that at certain positions of the member 32, such as when the pointer is at the extreme hot position, the element will be incapable of effecting sufficient movement of the member to lower it to depress the sleeve. In the first mentioned design, the temperature of the hot water dispensed from the unit will be kept under a certain maximum regardless of how high the temperature of the supply line may be. In the second design, however, there may be dispensed without interruption or variation a continuous stream at the full temperature at which the water is supplied. Thus even if the water in passage 23 is comparatively cool when the pointer is first moved to hot, the subsequent displacement of the cold by the hot water will not bring about a lowering 100 of the rod to effect movement of the sleeve.

With either of the foregoing designs, however, when the operator positions the pointer opposite or near "medium", the member 32 will be adjusted to an intermediate position on the rod 105 and the latter will cause member 32 to force the sleeve to the intermediate position with both sets of ports partially open. If the water in passage 23 has been hot, then as it becomes cooler with admission of the cold water, the rod will raise 110 sufficiently to cause the proper admixture of the water in accordance with the setting of the pointer. In the same manner should the water in the passage have been colder than that for which the pointer is set, the incoming hot water 115 will cause a lowering of the rod and the consequent like adjustment of the inlets.

It will be evident that should the pressure or the temperature in either of the water inlets vary from the normal, the increase or decrease in the 120 amount or temperature of the water then admitted in the passage will cause a corresponding raising or lowering of the rod and an adjustment in the positioning of the sleeve to compensate the abnormal or subnormal pressure or temperature. 125 For example, should the pressure of the hot water increase, the resultant lowering of the rod would cause a proportionate decrease in the extent of registration of the hot water ports and an increase in the amount of registration of the cold water 130 ports, thus still affording a water discharge from the unit in strict accordance with the temperature indicated on the dial. In the same way, should the pressure of the cold water increase, the additional amount of cold water admitted to 135 the passage will cause a contraction of the thermostatic element and the consequent elevation of the sleeve.

It is believed that the construction and operation of the unit of my invention, and its effective 140 accomplishment of the objects hereinbefore referred to, will now be clear.

I claim:

1. In a device of the character described, a mixing chamber portion with separate inlets for admitting relatively hot and cold fluids to the chamber portion, a valve unit in said chamber portion displaceable to decrease the flow from one inlet and automatically and correspondingly increase the flow from the other, a chamber portion into 150

which the liquid from the first chamber portion empties, a perforated partition separating said chamber portions, manually controlled means to move said valve unit to its different displaceable positions, a tubular thermostatic element fixed at one end thereof to said partition and extending into said second chamber portion, a rod secured to the other end of said element and extending centrally therethrough and through said partition and connected to said valve unit and operative on variation of the temperature in said chamber portion to move said means to displace said valve unit.

2. In a device of the character described, a mixing chamber portion with separate inlets for admitting relatively hot and cold fluids to the chamber portion, a sleeve fixed in said chamber portion having openings registering with said inlets, a sleeve mounted for reciprocation in said first sleeve and provided with openings registering with said first openings and displaceable to de-

crease the flow from one inlet and automatically and correspondingly increase the flow from the other, a chamber portion into which the liquid from the first chamber portion empties, a perforated partition separating said chamber portions, a hollow supporting post secured to said partition and extending into said first chamber, arms pivoted to said post and engaging for displacing said second sleeve to each of its different positions, a tubular thermostatic element secured at one end to said partition and extending into said second chamber portion, a rod secured adjacent one end to the other end of said element and extending centrally therethrough and through said partition and said post, a member threaded on the other end of said rod and engaging said arms, and a manually operable means engaging and rotating said member to actuate said arms and sleeve independent of the thermostatic element.
